US0D1020420S

(12) **United States Design Patent** (10) Patent No.: **US D1,020,420 S**
(45) Date of Patent: ** Apr. 2, 2024

(54) **POWER TOOL EXTENSION ROD**

(71) Applicant: **Zhiyuan Lou**, Zhengzhou (CN)

(72) Inventor: **Zhiyuan Lou**, Zhengzhou (CN)

(**) Term: **15 Years**

(21) Appl. No.: **29/900,252**

(22) Filed: **Aug. 18, 2023**

(51) LOC (14) Cl. **08-05**

(52) U.S. Cl.

USPC **D8/61**; D8/64; D8/97; D8/107

(58) Field of Classification Search

USPC D8/107, 61, 70, 64, 65, 95, 97

CPC B25F 5/02; B25G 1/04; B27B 17/0008;

A01G 3/08; A01G 3/085

(57) **CLAIM**

The ornamental design for a power tool extension rod, as shown and described.

DESCRIPTION

FIG. 1 is a top perspective view of a power tool extension rod, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the power tool extension rod, which form no part of the claimed design.

1 Claim, 6 Drawing Sheets
